UNITED STATES PATENT OFFICE.

WILLIAM DOUGLASS WOODWARD, OF PLATTSBURG, NEW YORK, ASSIGNOR
OF TWO-THIRDS TO ABNER L. ROBERTS AND MARTIN H. O'BRIEN, BOTH
OF SAME PLACE.

CAR-COUPING.

SPECIFICATION forming part of Letters Patent No. 366,990, dated July 19, 1887.

Application filed December 7, 1886. Serial No. 220,571. (No model.)

To all whom it may concern:

Be it known that I, WILLIAM DOUGLASS WOODWARD, of Plattsburg, in the county of Clinton and State of New York, have invented 5
5 a new and useful Improvement in Car-Couplings; and I hereby declare the following to be a full and clear description thereof.

The invention will be readily understood by reference to the accompanying drawings, of 10 which—

Figure 1 is an end elevation of a freight-car provided with my improved coupling. Fig. 2 is a side elevation of a portion of a freight-car provided with the said improvement. Fig. 3 15 is an enlarged sectional elevation of the coupling, taken longitudinally through the center of the draw-head. Fig. 4 is a transverse sectional elevation of the improved coupling, taken transversely through the draw-head and 20 the fulcrum of one of the operating-levers, showing the said lever or pin-lifter in elevation. Fig. 5 is a transverse section of the pin-lifter-lever fulcrum, showing the rocking fulcrum-pins of the said fulcrum-plate. Fig. 25 6 is an elevation of the clamping-bars which hold the lever-bar down when the coupling-pin is raised.

The draw-head A is attached to the framework of the car B in the usual manner, and it 30 is designed to receive and couple with the ordinary closed-link coupling. To facilitate the coupling-link C entering into the chambered link-recess *a* of the draw-head, I provide at the front end of the draw-head an inclined apron, 35 D, on which the link may strike when two cars come together, and the link will readily slide up on said inclined apron and enter the draw-head recess *a* without the necessity of a person going between the cars, thus making this practically a self-coupling device. The coupling-pin E is attached to the ends of a pair of transverse levers, F F', which are placed transversely to the car at the end thereof, and also 40 to a vertical lifter-rod, F², leading to the top 45 of the car, the whole lever mechanism so combined and constructed that it may be operated to lift the coupling-pin from either side of or from the top of the car, the handles of the lateral levers F F' extending to near the side of 50 the car, as shown in Fig. 1. The said levers

F F' have their inner ends coupled together by a coupling-link, f, and they, or one of them, is coupled to the pin E by a link, f', and the rod F² is also suitably attached to one or both of the said levers, so that if either one of the said 55 three lifting devices F F' F² be properly manipulated the pin E and the apron D, which is attached to the lever F by a connecting-rod or stirrup-piece, D', will be raised up as required. The rod or stirrup-piece D' is pivoted to the 60 lever F by means of an assembling-pin, d, passing through its upper end and through the said lever F, and its lower end is bent outwardly into an L-shaped form, so as to readily receive the metal plate forming the apron D, which is 65 riveted to it. The fulcrum of each of the said levers F F' consists of a bed-plate, G, bolted down to the top of the dead-wood piece B', or some equivalent part of the car, and a cradle-piece, G', coupled together by their respective 70 lug-pieces g and g' and the assembling-pins g², which pass through these lugs and assemble them together, so that the upper or cradle piece, G', of the said fulcrum may have a lateral rocking movement along with its attached 75 lever, which is pivoted in an upwardly-projecting lug or pair of lugs, g³, rising from the top of the cradle-piece G'. One of the lug-pieces g' extends downwardly below the pivot-pin g², and is turned outwardly into a lateral 80 arm, g⁴, which furnishes a bearing or guide for the lifter-piece D'.

A clamping device consisting of a pair of inwardly-toothed levers, H H', pivoted together by the assembling-pin h at their lower ends in a 85 plate, H², which is fastened to the side of the dead-wood piece B', or in an equivalent position on the car B, is designed to hold the free end of the lever F down when the pin E is to be held up. The upper ends of the said levers 90 or hooked holders H H' are provided with inwardly-projecting teeth or lugs h h², the upper faces of which slope upwardly and outwardly and the lower faces of which slope downwardly and outwardly, so the lever F may be pressed 95 down between the said lever-holders or up out of them by simply moving the lever down or up, as required, the two said holders or jaws being habitually thrown or held together sufficiently for this purpose by the actuating-spring 100

H^3 . In this manner the pin E may be raised and held up until the link of the approaching car shall have entered the draw-head of the car on which the coupling is set for automatic 5 operation, and when the draw-head of said approaching car strikes or presses against the apron D it forces said apron down and under the other draw-head, and consequently forces the lever F up out of the jaws $H H'$, and the 10 pin E then falls down into and through the link, and the coupling is then completed.

Having described my invention, I claim—

1. The lever F, mounted in and fulcrumed to the laterally-rocking cradle G', in combination

with the lever F' , lifting-rod F^2 , pin E, and 15 sliding apron D and its lifting rod or stirrup D', substantially as shown and described.

2. The lever-holders $H H'$, with their pivot 20 and actuating-spring H^3 , in combination with the actuating-lever F, substantially as shown and described.

In witness whereof I have hereunto set my hand in presence of two witnesses.

WILLIAM DOUGLASS WOODWARD.
